UNITED STATES PATENT OFFICE.

RALPH RILEY, OF AKRON, OHIO, ASSIGNOR TO THE MILLER RUBBER COMPANY, OF AKRON, OHIO, A COMPANY OF OHIO.

DESIGN FOR A DOLL.

Application filed October 18, 1922. Serial No. 4,020. Term of patent 14 years.

To all whom it may concern:

Be it known that I, RALPH RILEY, a citizen of the United States, residing at Akron, in the county of Summit and State of Ohio, have invented a new, original, and ornamental Design for Dolls, of which the following is a specification, reference being had to the accompanying drawing, forming part thereof.

The figure is a front elevation of a doll embodying my new design.

I claim:

The ornamental design for a doll, as shown.
